TRANSMITTING SYSTEM

Frank W. Jackson, Chicago, Ill., assignor to S. H.
Couch Company Inc., North Quincy, Mass.

Continuation of application Serial No. 716,829,
March 22, 1934. This application October 22,
1940, Serial No. 362,256

5 Claims. (Cl. 177—360)

This invention relates to signal transmitting systems generally and in its specific embodiment to a signal transmitting system that is adapted to be used in connection with fire alarm call boxes, sprinkler systems, and the like, and is a continuation of my prior application Serial No. 716,829, filed March 22, 1934, now abandoned.

This invention has particular application to sprinkler system installations such as are commercially known in industrial and plant hookups.

In larger sprinkler system installations where the pipe lines extend over large areas and also in buildings having several floors, there is customarily provided a central office in which there are located the principal equipment and annunciators for controlling and indicating the conditions of a sprinkler system and network which extends throughout the building or, where several buildings are concerned, which extend throughout the entire plant. In connection with such systems it is desirable to provide an annunciator that will accommodate an operator situated at the principal office and apprise him of the conditions throughout the entire plant.

It is accordingly an object of this invention to provide a signalling system of a compact and unitary structure that may be housed in a single cabinet and include a plurality of outlying signalling stations, the operation of any one or more of which serves to operate an annunciator and an alarm simultaneously and to thereby excite the attention of the caretaker at the central station, or, if preferred, to sound an alarm throughout the plant and to apprise of the location and nature of any disturbance occurring anywhere within the compass of the system.

The present invention contemplates, in addition, the provision of means for promptly checking its several circuits in order to assure a caretaker that its several parts are in proper operating condition and that the system is in readiness for receiving and responding to alarm signals that may originate at any of the several outlying stations.

The system contemplates also the provision of means for repeating an alarm signal a predetermined number of times to excite the attention of the caretaker and the provision of means for indicating by a signal individual to the calling station and to thereby apprise the operator of the identity of said station.

In carrying out these and other objects of the present invention, the system embodies in its preferred form the provision of a unitary cabinet structure which comprises a complete enclosure

5 or housing that may preferably be suitable sealed so as to render it dust and moisture proof and that is small and compact so as to be capable of ready installation in premises where economy of space may be especially desirable. The signalling lines radiating from the cabinet structure located at the central office extend throughout the plant and normally carry current or are energized so as to assure more positively the proper operation of the system in contradistinction with an alternative method of operation where the several lines normally carry no current and where reliance is placed upon the proper operating condition of each line. When any one or 10 more of the outlying stations is operated, it opens the line and causes the release of a normally energized relay associated with said station and located at the central office. When this occurs, a signal is stored representative of the 15 particular station, or where more than one station is operated at any given time, several signals are thus stored by storage relays.

Following this, a circuit condition is established in accordance with the first station operated, which condition responds to the travel of 20 a seeker or selector mechanism so that the latter, at a predetermined interval in a cycle of operation, causes finally the operation of a code signal a number of times corresponding numerically to the identification character of the station. The code is preferably repeated twice, and 25 at the conclusion of the second repetition a subsequent signal condition is established if another station has been operated preparing a circuit operable for this subsequent signal, and this 30 in cooperation with the seeker mechanism causes the tolling of the audible signal or operation of another form of signal.

In this manner the sequence proceeds in accordance with the natural arrangement of the 35 storage relays until the signals of each of the operated stations is transmitted and sounded, after which the system repeats until brought to rest by the restoration of the closed line condition in each of the several stations.

In addition to the foregoing, other features 40 of the present invention include the provision of a test circuit which is normally prepared and which is operative for indicating certain disorders in the local station equipment. In its preferred embodiment, this test circuit is associated with a parallel lighting circuit that passes 45 through each of several station indicating lamps, causing the latter to be lighted momentarily for the purpose of indicating by comparative con-

dition when any one of the lamps is burned out or when, due to any other reason, it fails to function. Concurrently, a trouble signal is sounded and a lamp lighted indicating to a caretaker that a local disorder has arisen and designating what adjustment need be made to reestablish proper condition.

For a better understanding of the present invention, reference should be had to the accompanying drawings, wherein like designating characters indicate similar parts throughout and wherein,

Figure 1 is a front elevational view of a cabinet structure embodying features of the present invention and having certain portions broken away to reveal the interior structure;

Figure 2 is a transverse sectional detail view taken approximately on line 2—2 of Figure 3;

Figure 3 is a detailed plan view of a portion of the mechanism illustrated in Figure 1.

Figures 4, 5, 6 and 7 combinedly indicate a wiring diagram embodying certain features of the present invention, and,

Figure 8 is a general perspective view of the cabinet structure embodying the features of this invention.

Having particular reference now to Figures 4, 5, 6 and 7, there is illustrated diagrammatically a wiring arrangement or hookup having a central station arbitrarily chosen for accommodating six outlying stations which, in accordance with a preferred embodiment, may correspond to various points located throughout an industrial plant or building where the present invention is to be applied. The switchboard terminals of these six stations, which themselves are numbered 21, 22, 23, 31, 32 and 33, are located at 21m, 22m, 23m, 31m, 32m and 33m. Between these latter points and the alarm common lead 213, are located station switching means which may be manually operated or controlled for operating the station point alarm, or which may also automatically be responsive to a predetermined condition such as, for example, the breaking of sprinkler heads, etc., which are so arranged to break the normally closed circuit with which each station is identified.

The six stations in the system, shown in the drawings are numbered 21, 22, 23, 31, 32, 33, which may be the code number for the stations; that is to say, 23, would be announced by two short signals followed by a pause, and then three short signals following, and if the station number is repeated, the successive station signal which will follow will be repeated after a longer pause than between the numbers of the station.

Each station has associated with it, in the present system, a number of independent elements including a line lamp numbered 21L, 22L, 23L, 31L, 32L, 33L which line or lines are signalling by going from a dim condition to full brilliance on the operated lines, a storage relay numbered 21T, 22T, 23T, 31T, 32T, 33T, two sequence relays, one, the upper of the pair, slow, and the other, fast, numbered 21Q, 22Q, 23Q, 31Q, 32Q, 33Q, a group of alarm terminals, 21M, 22M, 23M, 31M, 32M, 33M, and other elements to be mentioned later.

Each storage relay in the group is energized in normal operation in a circuit in series with the particular station which it represents; for instance, station 33 with the storage relay 33T is energized from the power line 212 in a circuit through this storage relay coil, through the contacts of the sequence relay 33Q, through the out-

side alarm box circuit to the resistor 214 and then to the other side of the line 204. Similar separate circuits are employed for the storage relays 32T, 31T, 23T, 22T and 21T. While the storage relays are normally current carrying relays, the sequence relays on the other hand normally operate in an open circuit condition with their contacts forming on both sides series circuits which are separate from each other forming negative side and a positive side with each set of series contacts. The positive line may be traced through the group of series contacts beginning at the positive line 203 through the connecting line 215 to the right contact RQ of the sequence relay 21Q through the connector 216 to the right contact RQ of the sequence relay 22, and so on up through each right contact RQ of the sequence relay including the transfer sequence relay and the relays 31Q, 32Q, and 33Q in series successively. The negative lines which are controlled by the slow acting relays may be traced from the negative side 203 through the conductor 217, the contact 218 of the final closing relay, the line 219 to the contact 220 at the left of the slow acting relay 33Q. Successively this circuit follows through the closed contacts 220 of the other sequence relays as far as the relay 21Q where the series ends and is connected to the positive line 203 through the coils of 21Q and the connector 216.

It will be seen from the above that each sequence relay is provided with contact switches the contacts of the slow acting coil in the negative side of the line and the contact of the fast acting coil in the positive side of the line, and that the lines are supplied with potential through the relays in reverse order; that is, the relay 33Q is at the beginning of the negative side of one line and at the end of the positive side of the other line. When therefore the storage relay gives way by a break in the system as when an alarm operates, or when one of the test switches 69 is opened, the sequence relay which first functions, will break the line at that point and make it possible for that particular sequence relay to operate and no other until that relay has been restored. For instance, assume that the storage relay for station 32 storage relay 32T has failed, thus releasing its contact α , which thereby will permit the energization of the sequence relay 32Q through the negative line 219 and through the positive line which may be traced through the connecting line 221, 222, 223 to the RQ switch of the sequence relay 31Q, and in a similar fashion through the transfer sequence relay and then through the relays 23, 22 and 21, to the positive conductor 203. The operation of the quick acting switch of the sequence relay 31Q will break the positive supply of current to the sequence relay 33Q and the action of the slow acting sequence relay will break the negative supply of current to the relays 31Q, transfer sequence relay, and the other sequence relays 23Q, 22Q and 21Q, permitting none of the other sequence relays to operate. When once the sequence relays have operated a number of other events occur.

The slow acting relay opens the contact SQ of the sequence relay thus keeping the circuit through the storage relay open until the sequence relay has been restored to normal. This will permit the program of the operation of the system to be completed without possible interruption by refunctioning of the storage relays before the cycle of operation has been completed. The sequence relays also operate the contacts for estab-

lishing the connections to the code drum 224. The code drum for six stations numbered 21, 22, 23, 31, 32, 33, is provided with seven contacts C1 to C7 inclusive. If the sequence relay has operated, the code contacts C32, C32, will be opened, thus opening the connections to the contacts C4 and C7 of the code drum which contacts normally would be supplied from the positive line 225 through the contactor relay coil 226, the time limit cut out 227 through the lines 203 and 204 to the positive side.

The supply of potential to the contacts of the drum through the switch contacts C21, C22, C22, C23, C23, C31, C31, C32, C32, and C33, is arranged as in the copending application Serial No. 305,442, filed November 21, 1939, and issued as Patent No. 2,263,877, November 25, 1941. The opening of the left contact of switch C32 opens the circuit which connects through the contact of C32 to the brush B4 which would otherwise complete contact with the contact C4 when the drum and brushes are rotated relatively to bring contact C4 beneath the brush. Similarly the right contact C32 opens the circuit for the line 229 which is directly connected to the brush B7 when the drum rotates relative to the brushes. The other brushes B1, B2, B3, B5, B6, will supply current to their corresponding contacts through the positive connection to the line 225 and cause the station number to be sounded, namely, three bells, a pause and two bells, indicating that the station 32 is operating.

The positive line of series contacts of the fast acting coil of the sequence relays form a closed circuit to the negative side of the line through the motor control relay coil 230, the slip ring segment 231, the slip ring 232, the line 217 to the negative connection 200. When the positive line is broken, for instance, as when sequence relay 32Q operates, the motor control relay coil 230 is deenergized and the contact 223 is made to the conductor 234, the line 217 and the negative side, thus energizing the motor 235 whose positive side is connected to the plus side 204. The motor 235 drives the selector 1, the selector 2 and the commutator segments 232, 231, 236, 237, 238 and 239, as well as the code drum 224, which however is geared 3 to 1 as regards the commutator units and selectors. Since the brush to the segment 231 and the segment move out of contact with each other, the motor relay coil 230 remains deenergized permitting the motor circuit to remain closed and the motor to continue to operate regardless of the condition of the sequence relay.

It will be noted that at any time any storage relay may operate other than the one which has already operated. Any such second storage relay will not bring about the operation of the second alarm until the signal sequence of the first has been completed. The operation of the motor sets in motion the various elements that complete the cycle.

The selectors 1 and 2 rotate at one third the rate that the code drum rotates and therefore two sets of signals are given out by the code drum before the selector brushes bridge the open contact of the sequence relay to allow another sequence relay to operate if the corresponding storage relay is open. The motor control relay circuit, after it is opened will remain open until the commutator segment 231 bridges the conductors 217 and 240, and the fast acting sequence relays are all restored by the closing of the circuits at all the operated alarm boxes. Therefore as long as any of the storage relays are not energized,

which will compel action of the sequence relays, the sequence of signals will continue to repeat themselves.

The system is so arranged that if a number of stations are simultaneously operated, as for instance by a fire in the plant or the operation of a sprinkler system so that the storage relay circuits are broken, the operation of the various stations will follow in sequence in the following order of rotation, 21, 22, 23, 31, 32 and 33. If during the operation of the alarm for one station, other stations act to break the circuit of their corresponding storage relays, the sequence which will be followed for the operation of the other stations will commence with the station of the next highest number to that giving the alarm when the new stations come into action. For example, if station 32 is sending its alarm and the storage relay for station 33 is deenergized, then the next station to operate will be station 33. If stations 21 and 22 also come in at the same time as station 33, then following the alarm given for station 33, station 21 and station 22 will operate and thereafter the signals will be repeated indefinitely in the order 21, 22, 32 and 33, with pauses between the signals for the various stations due to the gap in segment 236.

Before explaining the sequence of this system, some of the features of the circuit should be noted. The selector brushes 133 and 134 move clockwise about the selectors 1 and 2 respectively successively bridging the RQ contacts for the various stations in the following order. Station 33, stations 32 and 23 simultaneously, stations 31 and 22 simultaneously, the transfer sequence relay and station 21 simultaneously. It will be noted that the bridging of the RQ contact for station 32 when this station is operating, will complete the positive line through all the fast acting relay contacts and therefore close the positive line through the sequence relay 33Q to the contact α of the storage relay of station 33 which we assume has now opened the circuit and is waiting to give its signal to the negative line 219 and then through the contacts 218, the line 234 and the line 217 to the line 200 to the negative terminal. When this circuit has been completed the fast acting relay 33Q will immediately open the positive line beyond its RQ contact so that the final closing relay coil 243 will not operate. The slow acting relay coil will also be energized and open the contact 220 so that the negative line of all the lower station members will also be opened. Not only will it be impossible for any other station to operate, but it will be seen that the alarm signal will be transferred from station 32 to station 33. Since the positive line above the station 33Q remains open, the circuit to the motor control relay coil 230 will also be open and the motor will continue to turn as it did for the previous alarm signal. Therefore selectors 1 and 2 and all the commutator segments previously mentioned as well as the drum will continue to function. The signal now given by the drum will be given as three rings by the energization of the brushes B1, B2 and B3, a pause since the brush B4 is not energized, and three rings by energization of the brushes B5, B6 and B7. When the signal for the station 33 has been given, a station of the lower numbers may operate if its storage relay circuit has become open. Assume for instance that the storage relay of station 22 has been deenergized so that its contact α is made with a negative line. First it will be noted that the positive line through the RQ contacts are all

closed up to the station 33. The selector brush 133 in its rotation about the selector 2 first bridges the RQ contact of the sequence relay 33Q thus completing the positive line from the supply line 203 through all the RQ contacts through the final closing relay coil 243 through the commutator segment 237 which has moved into contacting position from the position shown in Figure 4, through the commutator ring 232 through the line 217 to the line 200. The bridging therefore of the RQ contact of station 33 energizes the final closing relay raising the contact 218 and thereby breaking the negative line to the contacts of the slow acting coils of the sequence relays. This action deenergizes the entire negative line and all of the sequence relays, thus keeping all of the RQ contacts closed and this condition continues until the segment 237 leaves its contact brush which occurs while the segments 239 still remain in contact with their corresponding brushes. When the segment 237 leaves the brush 237', the circuit to the final closing relay is broken, completing again the negative line 219 to the contacts of the slow acting sequence relay coils.

At this point therefore both negative and positive lines are completely restored and therefore the lowest numbered station will operate as explained before. In other words, since the fast acting coils would all operate before the slow acting coils, the first in series of the fast acting coils will be the station to control. While the positive line to the final closing relay 243 is completed, it should also be noted that the line to the motor control relay 230 is not completed since the circuit is broken at the commutator segment 231 at this moment because of the commutator position as previously mentioned.

After the station 21 has operated, the brushes 133 and 134 in connection with the selectors 1 and 2 short circuit the RQ contact of station 21 and therefore shift the operation to the station 22.

In the next cycle of the selectors 1 and 2, the RQ contact of station 22 when bridged by the brush 133 shifts the signal action to station 23.

When the RQ contact of the station 23 has been bridged, the transfer sequence relay will become energized through the negative line 219, the line 241, one of the brushes 239', a segment 239, the second segment 239, the second brush 239', the line 242 to one side of the sequence relay coils through the sequence relay coils and the sequence relay RQ contacts to the positive line 203. The completion of this circuit will operate the transfer sequence relays, deenergized its RQ contact preventing therefore the operation of stations 31, 32 and 33 until after the transfer sequence relays have become deenergized. The transfer sequence relays become deenergized when the brushes 239' leave the commutator segments 239 which is later in the cycle than when the brush 237' leaves the segment 237, so that in sequence of operation, first the final closing relay coil becomes energized opening the negative line 219 and then when coil 243 is deenergized by the moving of the segment 237 away from the brush 237' permitting the negative line 219 to become completed, the transfer sequence relay will operate preventing the operation of any of the stations 31, 32 and 33 until the beginning of the next cycle. By this means therefore the transfer sequence relay recycles the entire system.

Among the commutator segments, the code

segment 236 supplies potential to the code drums only throughout two revolutions of the drum and in the next revolution the code is silent.

Where the code for a station has been completed before the storage relay for the next station has operated, the sequence will of course follow the order of the operation of the various stations, but where simultaneously a number of storage relays have operated as for instance in a fire over a large area, the sequence is arranged to follow numerically from the smaller numbers to the larger numbers as explained above. In such cases if the lower numbers have been operated, the transfer sequence relays transfer to the next group of numbers. It is of course obvious that the transfer sequence relays may control other groups of stations so that thereby the same system may be extended.

Other auxiliary circuits will now be described.

The line lamp circuit may be traced from the negative line 200 Figure 7, through to the coil 291 of the line lamp supervisory relay then through the line 202 to the normally closed contact switch *b* of the storage relay 33T, then through the line lamp 33L and the switch *c* to the storage relay 33. The circuit through the line lamp then continues down through each one of the station line lamps through the switches *c* and *b* of the storage relay 32T and through the switch *b* of the storage relay 31T to the other side of the line 203 which connects as illustrated in Figure 7 through the conductor 294 to the plus side of the power supply. The line lamps of the twenty group, that is, 21L, 22L, and 23L, are connected similarly through the second line lamp supervisory relay 205 through the line 206 and the contact switches as follows:

Through the lamp 23L by means of the switches *b* and *c* of the storage relay 23T; through the switches *c* and *b* of the storage relay 22T and the lamp 22L, and through the switch *b* of the storage relay 21T and the lamp 21L; then to the positive terminal through the line 203.

It will be seen from these circuit connections that the line lamps in series will function as long as the line circuit is completed and the lamps are capable of transmitting the current through them. If any of the lamps of the thirty group give way, the line supervisory relay 201 will fail, while if any of the lamps of the twenty group give way, the relay 205 will fail, and this will be indicated in the line lamp trouble lamp 207, the circuit of which will be completed from the negative supply line 209 through the switch of either relay 201 or 205, the lamp 207 and the line 208, to the negative side of the low voltage source 209. At the same time that the line lamp trouble lamp glows, the operating trouble bell 210 will also ring, so that if the watchman or operator does not see the line lamp trouble, he will still hear the trouble bell. If desired the trouble bell may be cut out by the silence switch 211.

The test switches 69, if opened after a lamp failure will test which of the station lamps are good, as then the lamp is connected across the power supply. If 33L fails to light when its test switch is opened, the lamp 33L has failed; if 32L fails to light when its test switch is opened, 32L has failed; and 31L has failed if it does not light when its test switch is opened.

In Figure 5 all of the supervisory units are labelled and all are connected so that when any trouble occurs it may positively be indicated.

In the case of the motor circuit, it will be noted that the motor is operated directly across the

lines 200 and 204 when the motor control relay coil 230 releases the contact 233. When the motor control relay is holding, the circuit through the motor supervisory relay is completed through the line 200, the motor supervisory relay coil, the motor itself and the line 204. This circuit is such on account of the resistance of the relay that the motor will not operate. If for any reason the motor circuit fails, then the circuit to the motor supervisory relay is opened and this will be indicated by the lighting of the motor trouble lamp. In the case of the contactor supervisory relay, it will be noted that the coil of this relay is connected across from one side of the contactor relay across to the line 203. This circuit is such that if a break occurs in coil 226 of the contactor relay the contactor supervisory relay coil will become deenergized permitting the circuit to the contactor trouble lamp to be completed. The trouble supply supervisory relay will operate when the power supply fails to the trouble circuit.

In its preferred embodiment, all of the apparatus at the central station is housed within a metallic enclosure 155, Figures 1 to 6, with the main body portion 156 of which comprises a cover element 157 hinged at 158 and 159. The cover 157 is preferably close fitted to the box portion 156 and lined with suitable dust-proofing material so as to minimize the exposure of the contained apparatus to atmospheric and environmental conditions.

The cover portion 157 supports an enclosure housing 160 which contains the storage relays 21T, etc., and the signal lamps 21L, etc., in registration with which there are provided opalescent window elements 161, labeled to correspond with their associated indicating lamps 21L, etc. The cover 157 also supports the switch 69, of which there is one for each station, and a red colored window 162 through which is visible the signal lamp 207. The various lines which connect relays 21T, etc., and relays 21Q, etc., are conducted between the sub-enclosure housing 160 and the main body portion 158 together so as to form a cable 163, while the several lines 13 leading from the station points to the terminals 21M, etc., are likewise assembled together to form an outgoing cable 164 preferably passing through the wall section of the enclosure 156 through an insulating packing ring 165.

In Figure 2 there is shown in part by way of exemplification, the mechanism shown to the right of Figure 4 and the motor of Figure 5. The various brushes contacting selectors 1 and 2, the commutator ring, and the commutator segments are mounted on a brush carrier 93, while the selector and the commutators are mounted on a fixed drum 80.

The code drum 224 is driven by the gear 95 from the gear 96 which drives the brushes for the selector and commutator units.

The code drum 224 may be of the conventional distributor type, including an inner metallic cylinder 109 having fitted thereon a sleeve 110 of insulating material. Around the periphery of the drum 224, in a staggered spiral relation, are presented a series of cam projections or contactors 111, corresponding to the contacts C1, etc., of Figure 6. Each of these cam projections is in transverse alignment with one of the wiper blades B1, etc. The drum rotates in the direction indicated by the arrow 112.

The brushes for the selectors and commutator units are shown in the upper part of Figure 3.

The pairs 133 and 134 may correspond to those for selectors 1 and 2 and the brushes 117, 120, 140, 125, 124 and 123, may correspond to those for units 232, 231, 236, 237, 238 and 239, with corresponding convenient order and arrangement.

The drawings in Figures 1, 2, 3 and 8 are not intended to show detailed placements of the elements indicated in Figures 4, 5, 6 and 7, nor to show all the switches, relays, indicators, bell wiring or connecting terminals as showing would unnecessarily complicate the understanding of the invention. To this extent the showing in Figures 1, 2, 3 and 8 are exemplifications of how the mechanical mechanism coacts in the electrical circuit and functioning of the apparatus. The schematical diagram of Figures 4, 5, 6 and 7 is complete to show in detail the entire construction, functioning and manner of operation of the system when taken in connection with the description given before.

It should also be noted that this system is capable of a great many variations in structure and arrangement within the scope of the essential embodiments of the invention. The illustrations in the accompanying drawings and the foregoing description should not therefore be taken as limitations of the present invention, but merely as exemplary illustrations thereof, the true aspects of the present invention being indicated by the hereinafter annexed claims.

Having now described my invention, I claim:

1. In combination in an alarm system for a plurality of distributed stations, each identified by a particular code signal having a sequence relation one to the next in assigned groups, an independent normally energized circuit for each of said stations having local control means whereby the circuit may be broken for commencing the functioning of the alarm, a plurality of storage relay means, one operatively connected to each of said independent circuits and operative to store its station alarm for ultimate production, code means for producing the particular code signal identifying the station operated and means operatively associating said plurality of storage relay means with said code means for establishing and selecting the sequence of operation among the several stations operated including means for transferring from one group to the next.

2. In combination in an alarm system for a plurality of distributed stations, each identified by a particular code signal having a sequence relation one to the next in assigned groups, an independent normally energized circuit for each of said stations having local control means whereby the circuit may be broken for commencing the functioning of the alarm, a plurality of storage relay means, one operatively connected to each of said independent circuits and operative to store its station alarm for ultimate production, code means for producing the particular code signal identifying the station operated and means operatively associating said plurality of storage relay means with said code means, including a plurality of parallelly arranged sequence relays having armature contact elements for establishing the selected code and armature contact elements adapted to connect its relay across a pair of lines, one energized from one end, and the other energized from the other end, the one line having in series a slow acting armature of each of said relays, whereby the operation of any one of said relays will operate said

armature for establishing the selected code and prevent the operation of any other of said relays and means partly included in said lines for transferring the sequence of operation from one group higher in the sequence to one lower therein.

3. In combination in an alarm system for a plurality of distributed stations, each identified by a particular code signal, an independent normally energized circuit for each of said stations having local control means whereby the circuit may be broken for commencing the functioning of the alarm, a plurality of storage relay means, one operatively connected to each of said independent circuits and operative to store its station alarm for ultimate production, code means for producing the particular code signal identifying the station operated and means operatively associating said plurality of storage relay means with said code means, including a plurality of parallelly arranged sequence relays having armature contact elements for establishing the selected code and armature contact elements adapted to connect its relay across a pair of lines, one energized from one end, and the other energized from the other end, the one line having in series a slow acting armature of each of said relays, whereby the operation of any one of said relays will operate said armature for establishing the selected code and prevent the operation of any of said relays, and means for transferring the operation from one sequence relay to another when more than one storage relay has operated, comprising selector means for successively bridging the fast operating series armature contacts of each sequence relay whereby the next sequence relay in line may function.

4. In combination in an alarm system for a plurality of distributed stations, each identified by a particular code signal, an independent normally energized circuit for each of said stations having local control means whereby the circuit may be broken for commencing the functioning of the alarm, a plurality of storage relay means, one operatively connected to each of said independent circuits and operative to store its station alarm for ultimate production, code means for producing the particular code signal identify-

ing the station operated and means operatively associating said plurality of storage relay means with said code means, including a plurality of parallelly arranged sequence relays having armature contact elements for establishing the selected code and armature contact elements adapted to connect its relay across a pair of lines, one energized from one end, and the other energized from the other end, the one line having in series a slow acting armature of each of said relays, whereby the operation of any one of said relays will operate said armature for establishing the selected code and prevent the operation of any of said relays, and means for transferring the operation from one sequence relay to another when more than one storage relay has operated, comprising selector means for successively bridging the fast operating series armature contacts of each sequence relay whereby the next sequence relay in line may function, and a final closing relay, having a slow acting armature in the series circuit of the said slow acting armature, momentarily operative upon the bridging of the fast armature contact of the last of the operating sequence relays, for restoring all said sequence relays to normal inoperative condition.

5. In combination in an alarm system for a plurality of distributing stations, each identified by a particular code signal, an independent normally energized circuit for each of said stations having local control means whereby the circuit may be broken for commencing the functioning of the alarm, a plurality of storage relay means, one operatively connected to each of said independent circuits and operative to store its station alarm for ultimate production, code means for producing the particular code signal identifying the station operated, and means operatively associating said plurality of storage relay means with said code means for establishing and selecting the sequence of operation among the several stations operated, including means for transferring the operation from the code of one station to that of another station, and means for transferring the operation from one station of one code group to stations of another code group.

FRANK W. JACKSON.
